UNITED STATES PATENT OFFICE.

LEWIS TENNIS CANFIELD, OF CHICAGO, ILLINOIS.

TANK-CAR.

1,106,697.

Specification of Letters Patent. Patented Aug. 11, 1914.

Application filed November 1, 1912. Serial No. 729,078.

To all whom it may concern:

Be it known that I, LEWIS T. CANFIELD, residing at Chicago, Illinois, and being a citizen of the United States, have invented

5 certain new and useful Improvements in Tank-Cars, of which the following is a full, clear, and exact description, such as will enable others skilled in the art to which it appertains to make and to use the same, ref-

10 erence being had to the accompanying drawings, which illustrate the preferred form of the invention, though it is to be understood that the invention is not limited to the exact details of construction shown and described, 15 as it is obvious that various modifications thereof will occur to persons skilled in the art.

In said drawings: Figure 1 is a transverse sectional view of a tank car, the section being taken, at the right, just forwardly of the body bolster, at the left, substantially midway between the body bolsters. Fig. 2 is a side elevation of one end of a tank car of my invention. Fig. 3 is a half-plan view. 25 Fig. 4 is an end view of a modified form of tank, and, Fig. 5 is a fragmentary detail of a reinforce or brace within the tank.

As the parts at each end are duplicates, but half the car is illustrated.

30 This invention relates to improvements in tank cars and consists in certain features of novelty and utility, whereby a very simple and economical tank car adapted to all conditions of service is provided, and which 35 is of minimum weight.

In the construction of tank cars various types of devices have been used for anchoring the tank in position on the underframe, these devices comprising means which have 40 been secured at one or more places to the tank and to the underframe, or of head blocks secured to the underframe beyond the ends of the tank, or of anchor castings or stop devices depending from the tanks and 45 coöperating with various parts of the underframes, to prevent longitudinal shifting of the tanks on the underframes.

It has been supposed that it was necessary to construct tank cars in such manner that 50 the tank might be readily removed from the underframe for purposes of repair, and with the heavy type of underframe sometimes used, comprising center sills, side sills and intermediate sills, this is necessary, but 55 owing to the concentration of the load contained in a cylindrical tank, it has been

found in practice that but two center sills and two bolsters, or the equivalent of bolsters, are required. Associated with these, for convenience of the trainmen, are usually provided running boards upon which the trainmen may pass, and these running boards with their supports may be of light weight and readily removable from the tank and underframe.

There are disadvantages in the connection of tanks of tank cars to their underframes at intervals, owing to the unequal strain caused by service conditions. There is in some respects a disadvantage in a single 70 connection of the tank and underframe at the middle, owing to the fact that such middle connection serves as a rocking support upon which the tank may rock during buffing shocks, and thereby cause excessive 75 pounding at the bolsters, and there is also a disadvantage in the application of head blocks to the underframe beyond the tanks, because in such structures shifting of the tank causes the tank to impinge the head blocks placed between the bolsters and the end sills, thereby driving down the end sills and causing a drooping thereof, thus lowering the coupling below Interstate Commerce 80 Commission standard requirement.

It has been generally supposed that owing to the nature of the lading a tank could not be riveted to the underframe throughout its entire length, because it was believed that expansion of the tank, due to the filling of the tank with hot fluids, would set up enormous stresses which would rupture the rivet connection of the tank to the underframe when the tank would expand due to the heat of the lading. This latter theory has led 95 car builders to construct tank cars in which the tank was not fastened to the underframe at all, except by the conventional tank bands, and the tank was prevented from shifting 100 by various independent devices attached respectively to the tank and the underframe.

In this invention there are provided center sills 1, which have horizontal bottom flanges 2 and oblique top flanges 3, the center sills 1 being spaced apart the distance required by M. C. B. or other requirements; that is, about 13" apart. To the top flanges 3 of the center sills there is riveted directly the bottom sheet 4 of the tank by rivets 5, which pass through the bottom sheet 4 and the top flanges 3 of the center sills and the rivets 5 are provided at distances apart through-

out the entire length of said bottom sheet between the bolsters, thus riveting the bottom sheet of the tank rigidly and directly to the center sills.

5 If the bottom sheet 4 is of excessively thin material, rupture of the rivet connection referred to might occur, and to avoid this the said sheet 4 is preferably formed of a sheet of metal continuous from end to end 10 of the body of the tank and of relatively thicker metal than is the metal of the sheets 6, forming the major portion and the upper part of the tank. When a tank car is thus constructed it will be found that the tank 15 may expand in all directions when it is filled with hot fluid lading, and the rivet connection of the tank and underframe will cause a slight elongation of the underframe, but this elongation is so slight that it is 20 within the elastic limit of the metal comprising the center sills 1, and there is no real danger of a rupture of the rivet connection between the tank and said center sills.

If the rivet connection of the tank and 25 sills were excessively strong and intermittently arranged, there might and probably would be some danger of rupturing the rivet connection, but an equal distribution of the rivets 5 throughout the length of the tank 30 will cause the expansion of the tank to be transmitted through such rivet connection to the center sills and cause an elongation of such center sills, but always within the elastic limit of the metal comprising the center sills themselves. When the center sills and tank are thus connected and the underframe comprises only the center sills and bolsters plus such supports as may be necessary for running board, it will be found that 35 40 the tank and underframe may be readily lifted from the trucks, if necessary, for repairs.

Incidental to the details of construction hereinbefore referred to, I have provided a 45 bolster substitute, which comprises at each truck a pair of castings 8, which are formed with a perforated central web portion 9, and with reinforcing ribs or flanges 10, which latter define the perimeter of the casting 8, 50 with the exception of that portion of the outer edge thereof marked 11 in the drawings, which consists of a flange to which the running board supporting bracket 12 may be bolted; is best shown in Fig. 1, so that, if 55 necessary, said running board bracket may be removed.

It will be observed that the upper inner corner portion of the casting 8 is recessed at 13 to receive the upper flange 3 of the center sill, and that the upper surface of said casting 8 is concentric with the bottom sheet 4 of the tank, the top center sill flanges 3 being also concentric with said sheet 4, whereby a support conforming to the contour 60 of the tank is provided at each bolster.

It will also be noted that rivets 15 pass through the bottom sheet 4, and through the ribs or flanges 10 before referred to, thereby securing the tank in position with relation to the castings 8.

At the ends of the center sills there are provided substitutes for the conventional end sills, comprising horizontal angles 16 and the oblique angles 17, which are suitably connected with the top and bottom flanges 70 and with the webs of the center sills, the angles 16 and 17 being provided at each end of the underframe. Extending from end to end of the underframe at the outer ends of the angles 16 are angles 20, which serve as 80 ties for uniting the angles 16 and 17, the brackets 12, before referred to, and the supplemental brackets 21-22, which supplemental brackets serve as intermediate supports for the running boards 25, the angles 85 20 being riveted to the horizontal legs of the angles 21. Thus when it is necessary to remove the tank from the trucks, the running boards may be removed by withdrawing the bolts 30 which connect the brackets 90 12 and the angles 21 with their respective supports.

It is preferred that the side bearing 31 and center bearing plate 32 shall be formed separately from the castings 8, and said castings 8 at opposite sides of the center sills are connected by the bottom plate 33, rivets 34 passing vertically through the bottom flanges of the castings 8 and said bottom plate 33, and in some instances through the 100 bottom flanges 2 of the center sills and serving also to connect the side bearing 31 in proper position.

Figs. 4 and 5 illustrate within the tank a modification which may or may not be used, 105 and comprises a diaphragm 40 connected by angles 41 to the interior of the shell of the tank for the purpose of stiffening the tank above the bolsters, or at any intermediate points between the bolsters. Connected with 110 the center sills 1 are push pole pockets 42, which are preferably of cast metal formed with attaching flanges 43, to permit riveting said push pole pockets to the center sills. These push pole pockets are preferably placed, as shown in Fig. 2, forwardly of the bolsters and may be used where end sills are not applied to the cars. Where the running boards are supported other than as shown in the drawings, it may be an advantage to have the push pole pockets secured to the sills rather than, as is common, on the bolsters.

What I claim is:

1. In a tank car, the combination comprising spaced flanged center sills, the flanges of which are deflected upwardly, a tank comprising a plurality of body sheets and a continuous bottom sheet co-extensive with the length of said tank, said bottom sheet being 125 130

in continuous direct contact with and riveted directly to said upwardly directed flanges, a bolster connected directly to said sills and bottom sheet and a bottom cover plate uniting parts of said bolster directly to bottom flanges of the sills.

2. In a tank car, the combination comprising flanged center sills, a tank comprising a thick bottom sheet and relatively thin body sheets, said tank being secured by a rivet connection through said bottom sheet and co-extensive with the length thereof to the upper flanges of said center sills and being in direct contact therewith throughout substantially the entire length of said tank.

3. In a tank car, an underframe comprising only a pair of spaced center sills and bolsters comprising spaced castings provided with arcuate tops underlying portions of the center sills, and a tank in direct contact with and riveted to said sills by substantially equally spaced rivets practically throughout the length of said tank.

4. In a tank car, the combination comprising center sills and bolster castings, each casting adapted to conform to the curvature of a tank, and a tank resting in direct contact with said sills and bolster castings and riveted directly thereto, the tank being secured to the sills by substantially equally spaced rivets throughout its length.

5. In a tank car, the combination comprising an underframe consisting of longitudinal sills with tank-attaching flanges, bolsters with arcuate tops, the flanges of said sills resting upon, extending beyond and being connected to said arcuate tops, and a tank directly contacting with said flanges and also resting upon and being connected to said arcuate tops, said tank being substantially equi-distantly riveted to said sills throughout its length.

6. In a tank car, the combination comprising an underframe, and a tank in direct surface connection with and connected by direct rivet connection thereto substantially throughout the length of the tank and sills by equally spaced rivets, so as to develop the elasticity of the underframe during expansion of the tank.

7. In a tank car, the combination comprising an underframe having sills with upper and lower flanges and bolsters conformed to the contour of said sills and flanges and in reinforcing contact with each, and a tank in direct surface contact with said upper flanges and connected by direct and equi-distant rivet connection thereto for substan-

tially the entire length of the tank to substantially develop the elasticity of the underframe during expansion of the tank.

8. In a tank car, spaced center sills and a tank in continuous direct surface contact therewith throughout the length of said tank and secured directly thereto by direct rivet connection, the rivets being equally spaced so that the tank and sills mutually support each other throughout the length of the tank, and the sills may be caused to expand uniformly with the tank.

9. A tank car comprising a tank provided with a continuous bottom sheet, center sills connected rigidly to said bottom sheet by direct rivet connection and in direct surface contact therewith substantially throughout the length of the tank, the tank resting upon and being supported by the sills near its ends and supporting the sills without intermediate connection intermediate its end portions.

10. In a tank car, the combination comprising spaced channel-shaped center sills having their upper flanges deflected upwardly and a tank formed with a relatively thick continuous bottom sheet in direct surface contact with and riveted directly to said flanges and bearing directly on said flanges throughout its length.

11. In a tank car, a tank having a relatively thick bottom sheet, relatively thin sheets in the upper part of the tank, center sills in direct contact with and riveted directly to said bottom sheet throughout its length by equally spaced rivets, and body bolsters riveted to the tank and to said sills.

12. In a tank car, a tank formed of sheets of different thicknesses, the thicker of said sheets being a continuous bottom sheet, center sills in direct contact with said bottom sheet, and substantially equally spaced rivets passing through the bottom sheet and sills to secure them together throughout the length of said bottom sheet.

13. In a tank car, spaced sills, a superposed cylindrical tank in direct surface contact with and directly riveted to said sills by substantially equally spaced rivets throughout the major part of the length of said sills, and bolsters riveted to said sills and tank.

In witness whereof I have hereunto set my hand in the presence of two witnesses.

LEWIS TENNIS CANFIELD.
